WORK SHIFTING DEVICE

Harold C. Pierce, Pomona, Calif.

Application July 20, 1943, Serial No. 495,455

8 Claims. (Cl. 254—131)

This invention has for its primary object to provide a simple and low cost device for shifting heavy work of various kinds, typically filled boxes, barrels and the like in warehouses, freight cars, and other places where the loads may require shifting for alinement, or to fully occupy available space, or for any of other various reasons. The present device has proven particularly advantageous for adjusting the positions of individual, single or multiple tier units of boxed produce in refrigerator car loads.

In its preferred form, the device comprises an easily portable combination foot plate and lever assembly adapted to be placed on the floor adjacent the work, to engage the work with a bearing member or shoe carried by the lever. The foot plate has a bottom friction surface causing the device to resist displacement by reaction of the force applied to the work. A particular feature of importance is the mounting of the work-engaging shoe on the lever in a manner enabling the shoe to adjust itself to the vertical angularity of the work surface which it engages, and to remain in conformity with the work surface during the full range of movement of the lever. Also of special advantage is a simplified form of connection between the shoe and lever permitting easy disconnection and replacement of the shoe.

All the various features and objects of the invention, as well as the details of a typical and preferred embodiment, will be clearly understood from the description to follow, throughout which reference is had to the accompanying drawing in which:

Fig. 1 is a side elevation of the device with the shoe and foot plate appearing in cross-section;

Fig. 2 is a fragmentary section and plan taken on line 2—2 of Fig. 1; and

Figs. 3 and 4 are views illustrating typical shapes of replacement shoes.

Referring first to Fig. 1, the device comprises a base or foot plate 10 provided on its under face with suitable means, such as spikes 11 inserted within the plate, for frictionally engaging the floor to prevent movement of the plate away from the work as the work-shifting force is applied by the lever 12. An upstanding curved flange 13 is provided on the forward end of the foot plate 10 as a stop for positioning the operator's foot, which is placed on the plate to hold it in position against the floor. For purposes of simple and low cost manufacture, the forward portion, slotted at 14, of an initial plate stock, may be turned and bent upwardly to form arms 16 for mounting of the lever 12. The latter may be pivotally attached to

the arm 16 in any suitable manner, as by a pin 17 inserted through the parts as illustrated in Fig. 2. The arms 16 may be reinforced and held against spreading by a cross piece 18 welded to the arms at the back side of the lever.

The upper end 12a of the lever is turned at an angle, substantially as illustrated, and is provided with a hand grip 19. The lever carries at its lower end a work engaging shoe, generally indicated at 20, which preferably is mounted for such movement relative to the lever as to enable the face 21 of the shoe to conform with work surfaces having different vertical angularities, and to remain flatly engaged against the work during pivotal movement of the lever. While various types of connections permitting pivotal or rocking movement of the shoe relative to the lever may be provided, it is preferred to use a simple form of joint permitting disconnection and replacement of the shoe without having to manipulate any joint parts other than the shoe itself.

In its preferred form, the shoe 20 comprises a plate 22 having an integral lug 23 received within a clevis or bifurcated element 24 having sides 25 attached to the lever by pin 26, and a saddle piece 27 interconnecting the sides at the top. The back portion of the lug 23 normally is held in engagement with the under surface of the part 27 by a coil spring 28 connected by pin 29 to the lug, and by arm 30 to the lever 12. The shoe 20 has a bottom flange 31 which normally is engaged with the bottom surfaces of the sides 25 of clevis 24. As will be apparent, the work-shifting thrust is imparted to the shoe by the engagement of the lug surface 40 by the lever.

In its operation, the device is positioned with the shoe 22 adjacent or in engagement with the vertically extending surface of the work to be shifted, and the lever 12 is moved to press the shoe against the work. As shown in Fig. 1, the forward surface 21 of the shoe may normally have some small degree of inclination, or it may be truly vertical. According to the angularity of the work surface, and the extent to which the lever is moved, the shoe 20 may move in one direction or the other with relation to the lever. To illustrate, if initially the top portion only of the shoe is engaged with the work, application of force by the lever will cause the shoe to rock or turn on its flange surface of engagement with the under side of the clevis 24, the rear face of the lug 23 at all times bearing against and being supported by the lever. Conversely, if the work engagement initially is at the bottom portion only of the shoe, the latter is permitted to rock or turn at the sur-

face of engagement between lever 23 and the under side of member 27, ample clearance between the lug and lever being provided at 32.

The shoe may be disconnected from the lever simply by pulling the lug 23 out of the clevis 24. While in Figs. 1 and 2, the shoe is shown to have a working face in the form of a straight plate 22, it will be understood that various other shapes of shoes may be used, or substituted as the occasion demands. To illustrate, Fig. 3 shows a shoe 33 made of angular irons 34 arranged at 90° to fit the corners of boxes. In Fig. 4, the shoe 35 is formed of a curved plate 36 for application to the rounded surfaces of barrels and the like. The replacement shoes are drilled and tapped at 37 for insertion of the thread pin 29 to connect them with the coil spring.

I claim:

1. In a work shifting device of the character described, a foot plate having a bottom friction surface for engagement with a floor, an upstanding stationary support on said foot plate, a lever pivotally mounted intermediate its ends on said support, and a work engaging shoe carried by the lever at its lower end.

2. In a work shifting device of the character described, a foot plate having a bottom friction surface for engagement with a floor, a pair of upstanding stationary supports on said foot plate, a lever pivotally mounted intermediate its ends between said supports, and a work-engaging shoe carried by and movable relative to the lever to conform with the work surface as the lever is moved.

3. In a work shifting device of the character described, a foot plate having a bottom friction surface for engagement with a floor, an upstanding stationary support on said foot plate, a lever pivotally mounted intermediate its ends on said support, and a work-engaging shoe carried by and capable of swinging movement relative to the lower portion of the lever to conform with the vertical angularity of the work.

4. In a work shifting device of the character described, a foot plate having a bottom friction surface for engagement with a floor, an upstanding stationary support on said foot plate, a lever

pivotally mounted intermediate its ends on said support, a work-engaging shoe carried by the lower portion of the lever and movable from its normal position relative to the lever to conform with the work, and yielding means resisting movement of the shoe from said normal position.

5. In a work shifting device of the character described, a foot plate having a bottom friction surface for engagement with a floor, an upstanding lever pivotally mounted intermediate its ends on said foot plate, a member pivotally carried on the lower end portion of the lever, and a work engaging shoe associated with said member and movable independently thereof relative to the lever.

6. In a work shifting device of the character described, a foot plate having a bottom friction surface for engagement with a floor, an upstanding lever pivotally mounted intermediate its ends on said foot plate, a bifurcated member pivotally carried on the lower end portion of the lever, a work engaging shoe having a lug movably received within said member, said shoe being capable of rocking movement relative to the lever and independently of said member, and a spring resisting such movement of the shoe.

7. In a work shifting device of the character described, a metal foot plate having a bottom friction surface for engagement with a floor, a pair of upwardly extending twisted arm portions of the foot plate metal at one end of said plate, an upstanding lever pivotally mounted intermediate its ends between said arm portions, and a work-engaging shoe carried by the lower end portion of the lever.

8. In a work shifting device of the character described, a metal foot plate having a bottom friction surface for engagement with a floor, a pair of upwardly extending twisted arm portions of the foot plate metal at one end of said plate, an upwardly projecting foot stop on the top surface of said plate near said end thereof, an upstanding lever pivotally mounted intermediate its ends between said arm portions, and a work-engaging shoe carried by the lower end portion of the lever.

HAROLD C. PIERCE.
